UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

WAGON DRILL.

Application filed September 10, 1923. Serial No. 661,950.

To all whom it may concern:

Be it known that I, CHARLES C. HANSEN, a citizen of the United States, and a resident of Easton, county of Northampton, and 5 State of Pennsylvania, have invented a certain Wagon Drill, of which the following is a specification accompanied by drawings.

This invention relates to rock drills, but more particularly to supporting means 10 mounted on wheels, for rock drills, so that the drill may be conveniently moved from place to place.

In drilling deep holes, such as are required in quarry work, much difficulty has been 15 encountered and time expended in the changing of drill steels. Ordinarily, in drilling deep holes, a steel of short length having a comparatively large bit, is first used to start the hole, and thereafter the length of the 20 steels is increased, with a corresponding decreasing diameter of bit. In order to remove the steel each time, the operator must shut down the drill, lift the drill or in some way move the drill so that the steel is pulled out 25 of the hole, and consequently much time is wasted.

The primary object of the present invention, is to over-come the above difficulties, so 30 that a deep hole may be drilled without the annoyance of constantly changing steels.

Another object of the present invention is to provide a supporting mechanism for a rock drill, so that a comparatively long steel may be used, and the weight of the drill and 35 associated parts will feed the drill to work without any great effort on the part of the operator.

A further object of the invention is to produce a hoisting mechanism for a rock drill, 40 so that after the maximum depth hole has been drilled, the drill may be easily hoisted, thus enabling the drill steel to be readily removed.

A still further object of the invention is to 45 generally improve upon wagon drills with the view of constructing them more cheaply and sturdily, so that they may stand up under hard usage.

Further objects of the invention will hereinafter appear and the invention is shown in one of its preferred forms in the drawings, in which—

Figure 1 is a side elevation partly in vertical section of a wagon drill, 50
Figure 2 is an enlarged detail horizontal

sectional view taken on the line 2—2 of Figure 1, looking in the direction of the arrows,

Figure 3 is an enlarged top plan view of the supports and associated elements,

Figure 4 is a front end elevation of the 60 wagon drill shown in Figure 1,

Figure 5 is a horizontal sectional view taken on the line 5—5 of Figure 4 looking in the direction of the arrows,

Figure 6 is a perspective view of the cen- 65 tralizer, and

Figure 7 is an enlarged detail horizontal sectional view taken on the line 7—7 of Figure 4.

Referring to the drawings, A designates 70 the frame of a wagon, which is preferably composed of channel beams B and C secured in any suitable manner upon the cross beams D, which are mounted on the axles E and F carrying the wheels G, so that the wagon 75 may be conveniently hauled along the roadway, or across country and in a quarry.

A pair of upright supports H, preferably tubular in form, are secured to the brackets J', as by the bolts Q and nuts R. The 80 brackets J' are formed with curved portions which are adapted to slide over the tubular supports H, and trunnions J, pivoted on the blocks K, are carried by the brackets J'. The blocks K are secured to the channel 85 beams B and C, as by the bolts L and nuts O, and caps K' are in this instance bolted down over the trunnions J to the blocks K. Suitable diagonal braces P and cross braces P' are provided for the supports H and are 90 connected thereto by the bolts Q, nuts R and washers R'. The washers R' are formed with curved surfaces which are adapted to fit over the tubular supports H, and flat 95 surfaces against which the bolt heads and braces may bear, and in this manner the braces may be drawn up tightly against the washers. As shown in Figure 2, the diagonal braces and cross braces are secured to the supports by a single bolt on such support, and in this instance the brackets J' are formed with flattened portions J² against which a cross brace P' may bear.

In order that the supports H may be adjusted in an angular position relative to the 105 ground, a pair of legs S carried by the brackets T, are pivoted thereto on the bolts S' having washers T' on each side of the braces. The brackets T are formed with grooved portions which are adapted to em- 110

brace the supports H and are secured there-to by the cross bolts U and nuts V. The lower ends of the legs S are pivotally connected by pins X to brackets W, formed with flanges Y adapted to rest upon the upper portions of the channel beams B and C, and a series of holes Z are formed in the channel beams, so that the brackets W may be adjusted to the desired position by the insertion of bolts a in any of the desired holes Z, and in this manner the position of the supports H may be adjusted relative to the ground.

A cradle b having in this instance, curved end portions c, is located between the supports H, and the curved end portions are slideable thereon. A recess a' is formed in the cradle b within which any suitable rock drill d is adapted to be clamped by the plates e, bolts f and nuts g. In order that the drill d may be raised between the supports H, suitable hoisting mechanism is provided, and in this instance, a shaft h is secured to the supports H by the bolts j, nuts k, and washers o. The washers o have curved faces to fit the contour of the supports H, and serve to space the shaft h from the supports. A sheave p is preferably rotatable on the shaft h and a cable q is secured at one end to an eye bolt r carried by the cradle b and the other end is adapted to be wound on a suitable drum s, which is mounted on a bracket t, secured to the plate t'. A handle u is preferably connected by any suitable gearing to the hoisting drum s and provides means for manually winding the cable on the drum for hoisting the rock drill d.

A plate v is connected to the lower ends of the supports H by the bolts w, spacing washers x, and nuts z, and a reinforcing plate 2 is in this instance riveted to the plate v. In order to guide the drill steel 3 on starting a hole, a suitable centralizer or guide 4 is provided having recesses 5, which are adapted to be hooked over the plates v and 2, and a handle 6 enables the centralizer to be attached to or removed from the plate v, as desired. After the hole has been started, the centralizer may be removed by merely unhooking from the plate v.

In the operation of the drilling mechanism described, a long steel may be used, and the combined weight of the drill and cradle serve to feed the drill without any great amount of attention from the operator. After the desired hole has been drilled, the drill may be conveniently hoisted and the steel removed. The supports may be readily adjusted to compensate for changes in the surface of the ground.

I claim:

1. The combination with a frame, blocks carried by the frame, trunnions pivoted on said blocks, brackets carried by said trun-

nions, tubular up-right supports secured to said brackets, diagonal brace members, cross brace members, means for securing said cross brace members and diagonal brace members to the supports at one point, 70 a cradle to receive a rock drill, curved end portions on said cradle adapted to slide on said tubular supports, means for hoisting said cradle and a centralizer adapted to be removably connected to the frame for guiding 75 a drill steel.

2. In combination with a frame, blocks carried by the frame, trunnions pivoted on said blocks, brackets carried by said trunnions, tubular up-right supports secured to 80 said brackets, diagonal brace members, cross brace members, means for securing said cross brace members and diagonal brace members to the supports at one point, a cradle adapted to receive a rock drill, 85 curved end portions on said cradle adapted to slide on said tubular supports, means for hoisting said cradle, a plate connected to said supports, reinforcing means for said plate and a centralizer adapted to be hooked over said plate and reinforcing means for guiding a drill steel.

3. In combination with a frame including a pair of beams, a block mounted on each of said beams, a trunnion pivoted to each of 95 said blocks, a bracket carried by each of said trunnions, a pair of up-right supports connected to said brackets, bracing means for said supports including cross and diagonal braces, means for securing said bracing means to said supports including washers having a flat surface and a curved surface adapted to fit the tubular supports, a cradle movable on said tubular supports, and a centralizer adapted to be removably 100 connected to the frame for guiding a drill steel.

4. In combination with a frame including a pair of beams, a block mounted on each of said beams, a trunnion pivoted to each of 110 said blocks, a bracket carried by each of said trunnions, a pair of up-right supports connected to said brackets, bracing means for said supports including cross and diagonal braces, means for securing said bracing means to said supports including washers having a flat surface, and a curved surface adapted to fit the tubular supports, a cradle movable on said tubular supports, a plate connected to one end of said supports, 120 reinforcing means for said plate, a centralizer adapted to be hooked over said plate and reinforcing means for guiding a drill steel, and legs pivoted to said supports and adjustably connected to said frame for 125 varying the position of the supports relative to the ground.

In testimony whereof I have signed this specification.

CHARLES C. HANSEN.
